CLAIM

The ornamental design for an open-ended container system, as shown and described.

DESCRIPTION

This application is also related to U.S. patent application Ser. No. 29/400,158 filed Aug. 24, 2011, and to U.S. patent application Ser. No. 29/400,169 filed Aug. 24, 2011.

FIG. 1 is a front perspective view of a first embodiment of an open-ended container system embodying my new design; FIG. 2 is a side view of the open-ended container system of FIG. 1;

FIG. 3 is a top view of the open-ended container system of FIG. 1;

FIG. 4 is a front view of the open-ended container system of FIG. 1;

FIG. 5 is a back view of the open-ended container of FIG. 1; and

FIG. 6 is a bottom view of the open-ended container system of FIG. 1;

FIG. 7 is a front perspective view of a second embodiment of an open-ended container system embodying my new design; FIG. 8 is a side view of the open-ended container system of FIG. 7;

FIG. 9 is a top view of the open-ended container system of FIG. 7;

FIG. 10 is a front view of the open-ended container system of FIG. 7;

FIG. 11 is a rear view of the open-ended container system of FIG. 7; and,

FIG. 12 is a bottom view of the open-ended container system of FIG. 7.

The broken lines shown are included for the purpose of illustrating an environment of the article and form no part of the claimed design.
